CLAIM

The ornamental design for a buckle member for bag as shown and described.

DESCRIPTION

FIG. 1 is a front, top, and right-side perspective view of a buckle member for bag, showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken along line 8-8 shown in FIG. 2;

FIG. 9 is a back, top, and left-side perspective view thereof; and,

FIG. 10 is a perspective view showing the buckle member for bag in a state of use.

The long dash short dash broken lines and arrows shown in FIG. 2 are used to identify the cross-sectional view and form no part of the claimed design. The portions of the buckle member for bag shown in broken lines in FIG. 3 form no part of the claimed design. The broken lines shown in FIG. 10 depict environment and form no part of the claimed design.

1 Claim, 4 Drawing Sheets
